BASKET COOLER

Thomas S. Roussel, 327 Court St.,
Keene, N.H. 03431

Filed Mar. 31, 1975, Ser. No. 563,859

Term of patent 14 years

Int. Cl. D3—01

U.S. Cl. D7—77

FIG. 1.

FIG. 2.

FIG. 3.FIG. 4.FIG. 5.FIG. 1 is an exploded front perspective view of a basket cooler showing my new design;

FIG. 2 is an exploded left rear perspective view thereof, it being understood that the basket weave omitted for convenience of illustration is similar to that shown in FIGS. 1 and 5;

FIG. 3 is a top view thereof;

FIG. 4 is a section taken along line 4—4 of FIG. 3 with the pivoted handle omitted therefrom; and

FIG. 5 is a right side view thereof.

I claim:

The ornamental design for a basket cooler, as shown and described.
